VENTILATED WATER CLOSET OR TOILET

Joseph G. Schotthoefer, Detroit, Mich.

Application May 3, 1941, Serial No. 391,796

14 Claims. (Cl. 4—215)

This invention relates to a ventilated water closet or toilet.

The invention is particularly concerned with a toilet embodying the usual bowl and flush tank elements and having associated therewith regulatable means for causing escape of foul gases from within the bowl to and through the flush water outlet, as well as means to prevent the flow of foul gases from said water outlet to within the bowl.

It is appreciated that various forms of ventilated toilets have heretofore been constructed or proposed which embodied the ventilating means as a unitary part of the toilet or as attachments adapted to be installed with standard toilet constructions.

Such prior constructions, however, failed to successfully meet the maximum requirements of a ventilated toilet for various reasons, most important of which are enumerated as follows:

Many of such prior constructions involve a fan to create a gas suction and while by such means the foul gases may be effectively discharged, such fans created an uncomfortable or objectionably cool sensation to the user of the toilet.

Furthermore, such constructions are relatively complicated and include many parts external to the bowl and tank, thereby providing an unsightly appearance as well as a toilet structure capable of collecting dust and unsanitary accumulations, and in these complicated structures, in which a large number of elements are embodied, the chances of breakage or inoperativeness thereof are substantially increased.

In some of these prior constructions, a flow of water at relatively high velocity is utilized to create a partial vacuum to draw the foul gases from the toilet bowl. These constructions are open to objection on the grounds of complicated mechanism and also to the fact that an objectionably large volume of water is used in their operation.

The heretofore proposed constructions in the form of attachments are particularly objectionable in that substantially the same amount of labor is required to install them as is required to install a complete toilet and, furthermore, such attachments or parts thereof are exterior of the bowl and tank, thereby offering the same objection as above noted in connection with the unitary constructions.

A primary object of this invention is the provision of a ventilated water closet or toilet wherein the entire mechanism is completely enclosed as a unit within the toilet casing structure, and

which is operable by the usual flush tank handle.

A further object of the invention is the provision of a ventilated water closet or toilet having incorporated within the bowl and flush tank thereof ventilating means embodying a valve-controlled water tube in communication with the water feed line, the water tube having small apertures upwardly directed to prevent clogging and so that the small streams of water strike the adjacent concaved baffle slightly tangent thereto, thereby reversing their direction and converting the small solid stream into forcibly descending drops, guided by the baffle apron down the center of the channel to provide a partial vacuum therein. This action causes foul gases to be withdrawn from within the toilet bowl and discharged into the flush water outlet, the ventilating means further including a closable opening to prevent return of foul gases when the ventilating means is inoperative upon closing of the valve, and common means actuatable by the flush handle for simultaneously opening the valve and port and simultaneously closing same.

A still further object of the invention is the provision of a unitary ventilated water closet or toilet which involves relatively few simple parts completely enclosed within the toilet housing.

A still further object of the invention is the provision of a ventilated water closet or toilet in which the foul gases are drawn from the bowl by a suction caused by a rapid succession of drops of water within a channel in communication with the bowl, the water drops being delivered by a valve-controlled tube having small apertures, whereby a relatively small volume of water is used even though the valve be left open for a substantially long period of time.

For a more complete understanding of the objects and nature of the invention, reference will be had to the following detailed description, taken in connection with the drawings, wherein:

Figure 1 is a vertical sectional view of the improved ventilated water closet or toilet in accordance with a preferred embodiment of my invention.

Fig. 2 is a front elevational view of the toilet with the seat in raised position.

Fig. 3 is a fragmental enlarged sectional view of the rear portion of the seat and adjacent parts.

Fig. 4 is a similar view of the front portion of the seat and adjacent parts.

Fig. 5 is a top plan view as observed in the plane of line 5—5 in Fig. 1.

Fig. 6 is a horizontal section in the plane of line 6—6 in Fig. 1.

Fig. 7 is a fragmental elevational view of the flush tank supply line and the float controlled check valve.

Fig. 8 is a view partly in side elevation and partly in vertical section of the ventilator control means.

Fig. 9 is a view corresponding to a portion of Fig. 8 showing another position of the control means.

Fig. 10 is a vertical sectional view substantially in the plane of line 10—10, Fig. 8, with a portion of the tank casing shown in vertical section.

Fig. 11 is a horizontal section on line 11—11, Fig. 10, with certain parts omitted for clarity of illustration.

Fig. 12 is a top plan view of a swing port cover embodied in the construction.

Fig. 13 is a right-hand elevation of Fig. 12.

Fig. 14 is a hinge plate embodied in the construction.

Fig. 15 is a broken plan view of the flush actuating crank means.

Fig. 16 is a top plan view of a combined valve and cover actuating cam.

Fig. 17 is an end view of an abutment sleeve.

Fig. 18 is a side view thereof.

Fig. 19 is a broken side elevational view of the ball actuating arm.

Fig. 20 is a top plan view of a portion of same.

Fig. 21 is a side view of a second abutment sleeve embodied in the construction.

Referring now in detail to the drawings by reference characters, and wherein like characters designate like or corresponding parts in the different views, the letter T designates the ventilated toilet or water closet in its entirety and which essentially embodies a bowl B and flush tank F.

The bowl and tank are generally of usual or standard construction and may be unitary or the tank may be separated from the bowl in the plane of the line 5—5 as herein indicated.

In conformity with usual practice the water supply pipe s has associated therewith the float-controlled check valve c. The flush tank F is provided with the usual ball b having a lifting rod r guided by an overflow pipe o. The ball b cooperates with the cupped upper end of the nipple n whose lower end enters chamber m which, as usual, encircles the rim of the bowl B where it is provided with apertures a for admitting flush water within the bowl trap t whence in flushing the water discharges through the flush outlet tube f.

The structure so far described is of standard construction and the bowl B and tank F are in accordance with this invention modified for incorporation of the improved ventilating mechanism.

The bowl B in accordance with this invention embodies in addition to the usual parts a chamber 10 having the apertures 11 in its bottom wall for the nipple n and a port 12 communicating with the chamber 10 at one end thereof and having its other end open adjacent the rear of the seat S. The seat S has suitably secured to its lower side a somewhat oval-shaped rubber strip 13 having small horizontally disposed air ports 14 adjacent the front of the seat S.

The port 12 connecting chamber 10 with bowl B is substantially on an incline as shown and is also above the level of the bowl ring, so that in 75

case the bowl is flooded nothing unsanitary can lodge therein.

The rubber strip 13 terminates in spaced parallel ends 15 which in the closed position of the seat engage the end wall 16 at the open end of the port 12 and a short transverse rubber strip 17 extends over the ends 15 and bridges the space between the rear of the seat and said end wall 16, and is clearly indicated in Fig. 3.

Thus it will be seen that when the seat opening is closed by the usual lid or by a person using the toilet air is admitted only through the small ports 14, between the rubber strip ends 15, through port 12, and into the chamber 10.

15 The bowl B is further modified in the provision of a chamber 18 to the rear of the discharge tube f and an opening 19 is provided in the wall separating the tube f and chamber 18. The chamber 18 tapers down from top to nearly round in cross-section and before opening 19 in its course to make ample room for bubbles or foam that may result from forced water to pass through opening 19 without obstruction.

20 The flush tank F is modified to the extent of providing same with a substantially thickened rear wall and forming in said wall vertical channels 20 and 21 which preferably extend the full height of the tank with the upper end of said channel-providing wall defining a control mechanism seat 22 on which as well as the front wall of the tank the rim of the usual tank lid 7 rests. The channels 20 and 21 respectively communicate with chambers 10 and 18 at their lower ends and the upper ends of the channels open through 35 said seat 22.

25 Suitably supported on the seat 22 is a housing 23 through which extends substantially centrally thereof a small tube 24 having one end thereof plugged as at 25 and the opposite end thereof 40 in communication with a valve casing 26 having a valve 27 secured to and movable to open and closed position relative to the valve seat 28 by means of a stem 29 mounted for vertical sliding movement in the valve casing head 30 and a bearing 31 provided by the lower end of the valve casing.

30 The valve casing 26 is in communication with the water supply pipe s through a pipe connection 32.

35 The tube 24 is provided with a plurality of small apertures 33 in its upper side wall within the housing 23 whereby jets of water will emerge therefrom when the valve 27 is open, as indicated in Fig. 8.

40 A baffle plate 34 is suitably supported within the housing 23 and includes a downwardly concave deflector portion 35 merging into a substantially vertical apron 36 which, adjacent its lower edge, is preferably slightly roughened and of wave or corrugated form.

45 As indicated in Fig. 10, the apron terminates adjacent the upper end of the channel 21 and the apertures 33 are of such size that only a sufficient volume of water will be sprayed onto the baffle plate that it will emerge from the apron 36 in successive drops. However, the water will impinge upon the baffle under relatively high pressure which will not be substantially diminished in the drops descending vertically from the apron 36. These successive water drops, traveling under relatively high velocity, will effect a partial vacuum with the result that foul gases will be drawn from the bowl B upward through channel 20 and thence carried down the channel 21 and escape through the opening

18, the small air ports 14 in the rubber strip 13 accounting for the suction effect through the channels above described.

The present invention includes simple means for operating the valve 27 and simultaneously checking the return of foul gases by way of channels 21 and 20, respectively. This means in its preferred form is manually operable through manipulation of the usual flush handle whose shaft 37 is rectangular in cross-section throughout the major portion of the length thereof, the shaft terminating in a cylindrical portion 38 which is freely rotatable in a cam member 39 including a cylindrical portion 40 rotatably journaled in a plate 41 integral or rigid with the valve casing 26.

The cam 39 further includes a cam portion 42 which is embraced by a fork 43 of an arm 44 pivotally connected to the plate 41 at 45.

The arm 44 is provided with a pair of abutment lugs 46 and 47 between which the oval-shaped head of the valve stem 29 rests with opposed convex faces of the head engaging the respective lugs and the lug 46 is recessed as at 48 to receive the stem 29. Thus, as the cam 39 is oscillated clockwise and counter-clockwise the arm 44 will be rocked about its pivot 45 to respectively open and close the valve 27 according to Figs. 8 and 9, respectively.

The cam 39 further includes an arm 49 having an aperture 50 in which is pivotally connected one end of a rod 51 whose opposite end is pivotally connected at 52 to a lever 53 having a pivot stud 54 extending through a wall of the housing 23 and the lever terminates beyond the pivot stud in a disc weight 55 adapted to contact a stop lug 56 on the housing 23 in the open position of the valve.

A lever arm 57 is secured to the pivot stud 54 as by a cotter 58 and the lever arm is adapted upon oscillation of the pivot stud to project through an opening 59 in the top wall of a chamber 60 within the housing 23, the chamber being in communication with the upper end of the channel 20.

A cover 61 having opposite end trunnions 62 is pivotally supported on the top wall 63 of the chamber 60 by means of the pivot plates 64 having apertures 65 to receive securing devices to extend into apertures 66 in walls of the housing 23.

The cover 61 closes the opening 59 under gravity and is lifted from closed position as in Fig. 10 by means of the lever arm 57.

As will be seen from Figs. 8 and 10, the cover 61 is raised from the chamber opening 59 when the valve 27 is open whereby the upper ends of the channels 20 and 21 are in communication for flow of the foul gases in the manner above described, but upon closing the valve 27 by swinging arm 44, as in Fig. 9, the lever arm 57 will be rocked to permit gravity closing of the cover 61 to prevent reverse movement of foul gases upward through the channel 21 and downward through the channel 20.

The flush handle shaft 37 is rotatable counter-clockwise to flush the toilet as usual and for this purpose has a contact sleeve 68 secured thereto as by a cotter extending through the cooperating apertures 69 and 70, and this contact sleeve cooperates with a lever arm 71 rotatably supported on the shaft 37 between the contact sleeve 68 and a cotter to extend through an aperture 72 in the shaft.

The sleeve 68 and arm 71 are provided with 75 to claim 1, wherein the last mentioned means

the respective contact lugs 73 and 74 for engagement upon counter-clockwise rotation of the shaft 37 whereby the lever arm 71 will be rocked to lift the flush ball 7 through the usual connection between the ball rod 7 and the apertured end 75 of the lever arm. Thus, this arrangement permits movement of the lever arm 71 upon counter-clockwise rotation of the shaft 37 but upon clockwise rotation of the shaft the contact lugs 73 and 74 will separate and the lever arm 71 will not be moved.

The shaft 37 is adapted upon clockwise rotation thereof to rotate the cam 39 as in Fig. 8 to open the valve 27 and cover 61 to put the ventilating system into operation and for this purpose a second contact sleeve 76 is secured against axial movement to the shaft as by a cotter extending through the cooperating apertures 71 and 78, and this sleeve is provided with a contact lug 79 having a face 80 to engage a face 81 of a contact lug 82 on the cam 39 to open the valve 27 and cover 61, and the lug 79 is provided with a second face 83 to contact a face 84 on the lug 82 to move the cam 39 counter-clockwise for closing the valve 27 and cover 61.

Thus, the ventilating arrangement is capable of being put into operation by swinging the handle H upward, as indicated by the arrow in Fig. 2, and being put out of operation by swinging the handle down again to its normal horizontal position.

The toilet is capable of being flushed upon downward movement only of the handle H in the direction of the arrow in Fig. 2, and during this movement the cooperating abutment lugs 79, 82 will recede and no movement will result in the cam 39.

It will be appreciated from the foregoing disclosure that a ventilated water closet or toilet is provided by this invention which is unitary in construction, presents the same external appearance as the usual water closets or toilets and which includes relatively simple ventilating mechanism capable of being put into or out of operation by turning the flush tank handle upwardly in a clockwise or counter-clockwise direction, respectively.

Furthermore, the cooperating parts are simple and not liable to get out of order and by the use of a relatively small volume of water as a vacuum forming means to discharge the foul gases, maximum economy in operation is attained.

While I have disclosed but a single specific embodiment of my invention, the same is to be considered as illustrative only and not restrictive, the scope of the invention being defined in the subjoined claims.

What I claim and desire to secure by U. S. Letters Patent is:

60. 1. A ventilated water closet or toilet comprising a bowl and associated flush tank having a flush-operating handle, a pair of vertical parallel channels within the tank, the lower end of one channel communicating with the flush outlet of the bowl through a chamber in the bowl communicating with the channel, the lower end of the other channel communicating with the bowl, means for selectively creating a partial vacuum in one of said channels, means for selectively effecting communication between the upper ends of said channels, and means for simultaneously operating both of said first means.

2. A ventilated water closet or toilet according

comprises cam and lever mechanism operatively connected with the flush-operating handle.

3. A ventilated water closet or toilet according to claim 1, wherein said first means comprises a valve-controlled water pipe having a plurality of apertures in its wall adjacent one end thereof, and a baffle plate adjacent the apertures and including an apron terminating adjacent the upper end of said first channel, the baffle causing the water to forcibly descend within the channel in the form of successive drops for creating said partial vacuum therein.

4. A ventilated water closet or toilet according to claim 1, wherein said second means comprises a cover-closable opening between the upper ends of said channels.

5. A ventilated water closet or toilet according to claim 1, wherein a seat is hingedly secured to said bowl and provided with a rubber strip for engagement with the top of the bowl, the strip terminating in parallel ends rearwardly of the seat, and a short rubber strip superposed on said ends defining an opening in communication with said second channel.

6. A ventilated water closet or toilet including a bowl, having a flush outlet, a normally interrupted passageway interconnecting the top of the bowl and said flush outlet, means including an apertured pipe and associated baffle plate for forcibly projecting water drops through the passageway to draw foul gases therethrough and from within the bowl to said flush outlet, and means for operating said first means and simultaneously removing the interruption in the passageway.

7. A ventilated water closet or toilet comprising a bowl, having a flush outlet and associated flush tank having a flush-operating handle, a housing within the tank adjacent the top thereof, a pair of channels extending vertically within the tank and having their respective lower ends communicating with the top of the bowl and the flush outlet thereof, the upper ends of the channels communicating with the housing, means within the housing for effecting suction through the channels to draw foul gases from within the bowl to said flush outlet, means within the housing for selectively opening or closing the upper end of one of said channels, and means operable by the flush-operating handle for effecting opening or closing of said channel and rendering said first means operative or inoperative simultaneously therewith.

8. In a water closet or toilet comprising a bowl and an associated flush tank having a handle swingably mounted thereon for movement to opposite sides of a normal inoperative position and being operative to flush the bowl upon movement in one direction from said normal position; bowl ventilating means, and operative connections between said means and handle to render said ventilating means operative upon movement of the handle in a direction opposed to the flushing movement and inoperative upon return of the handle in the first direction to its normal position.

9. A ventilated water closet or toilet comprising a bowl and an associated flush tank having a flush operating handle, a channel leading from

the top of the bowl to a point adjacent the top of the flush tank, a second channel communicating with the first channel and leading to the flush outlet of the bowl, means normally interrupting communication between the channels, means operatively connected with the handle for creating a downward suction in the second channel with a resulting upward movement of foul gases in the first channel and thence downwardly in the second channel through the flush outlet of the bowl, and means connected with the handle for placing said channels in communication concurrent with the creation of a suction in the second channel.

10. A ventilated water closet or toilet comprising a bowl and associated flush tank having a horizontal flush-operated shaft provided with an actuating handle, flush means within the tank connected with the shaft for operation upon movement of the handle in one direction, and ventilating means having operating mechanism within the tank above said shaft and connected therewith for operation thereby upon movement of the handle in the opposite direction.

11. In a water closet or toilet comprising a bowl and an associated flush tank having a horizontally disposed operating shaft therein operatively connected with the flushing mechanism, and a normally horizontal handle secured to the shaft externally of the tank and operative upon downward movement thereof to flush the bowl; ventilating means for said bowl operatively connected with said shaft for being rendered operative and inoperative upon upward movement of said handle and return movement thereof to said horizontal position respectively.

12. In a water closet or toilet including a bowl having an outlet and an associated flush tank having an oscillatable shaft supported therein and operatively connected with the flushing mechanism, and a handle externally of the tank for actuating said flushing mechanism upon movement of the handle in one direction; ventilating means for said bowl comprising a housing supported above said tank, a passageway interconnecting the housing with an upper zone of the bowl, a second passageway interconnecting the housing with said outlet, valve controlled means for discharging drops of water through said second passageway toward said outlet to draw foul gases from said bowl and discharge same through said outlet, and means operatively connected with said shaft for operating said valve upon movement of said handle in another direction.

13. The structure according to claim 12, wherein in said valve-controlled means comprises a tube having a plurality of water-discharging apertures, and a baffle member cooperating with said tube and disposed to discharge drops of water into said second passageway.

14. The structure according to claim 12, together with means within said housing for placing said first passageway out of and into communication with said second passageway, and means operative by said shaft for actuating said means concurrent with the operation of said valve.

JOSEPH G. SCHOTTHOEFER.
